UNITED STATES PATENT OFFICE.

KEMP E. SAVAGE, OF NORFOLK, VIRGINIA.

DESIGN FOR A WATCH-CHARM OR SIMILAR ARTICLE.

No. 38,331.

Specification for Design.

Patented Dec. 4, 1906.

Application filed September 28, 1906. Serial No. 336,649. Term of patent 3½ years.

To all whom it may concern:

Be it known that I, KEMP E. SAVAGE, a citizen of the United States, residing at Norfolk, in the county of Norfolk and State of Virginia, have invented a certain new, original, and ornamental design for a Watch-Charms or Similar Article, reference being had to the accompanying drawing, which shows a plan view of the charm.

I claim—

The ornamental design for a watch-charm or similar article as shown.

KEMP E. SAVAGE.
